RADIO RECEIVING SYSTEM

Richard Eugene Mathes, Westfield, N. J., assignor
to Radio Corporation of America, a corporation
of Delaware

Application November 2, 1934, Serial No. 751,133

6 Claims. (Cl. 250—20)

My present invention relates to the radio signaling art, and to generally improve radio reception is one object of my present invention.

More particularly, my present invention is directed towards a super-heterodyne receiving system in which intermediate frequency energy is kept substantially constant in frequency despite relative variations in the transmitted signal frequency and the local oscillator frequency used for heterodyning purposes. Another object of my present invention is to provide an improved method and improved apparatus for maintaining this constancy of intermediate frequency. In accordance with my present invention, I carry out this object by frequency multiplying local oscillator energy to such a value that the beat between the frequency multiplied energy and the received signal energy corresponds in frequency to the frequency of the local oscillator. The beat energy is made of relatively large amplitude and is used to lock the local oscillator in step therewith. Should there be any relative variation in frequency to cause a change in the absolute value of the intermediate frequency, the local oscillator is varied in such a way that the frequency multiplied output is changed in extent and direction as to cause the beat frequency to become the constant value desired.

Still another object of my present invention is to provide a constant beat frequency arrangement for a receiving system utilizing a plurality of separated antennae. Other purposes and advantages of my present invention will be self-evident as the further description thereof proceeds.

As required by law, my present invention is defined with particularity in the appended claims. However, it may best be understood as to its structural organization and mode of operation by referring to the accompanying drawing which illustrates in schematic wiring diagram form my present invention applied to a receiving system making use of a multiplicity of separated antennae.

In the embodiment of my invention shown in the accompanying drawing, two receivers R_1 and R_2 are in the same direction and some distance removed from the central office C. O. and the receivers and central office are all connected by the same cable line or other tone channel facilities, which facilities can be made suitable to "carrier frequency" operation.

A local oscillator LO is set up at the receiving station nearest the central office and is adjusted, for example, to a frequency one-sixteenth of that

of the transmitter (not shown). The oscillator LO is adjusted to give feeble oscillations only and feeds a two stage combined frequency multiplier and amplifier FM1 and FM2. The first stage FM1 multiplies the oscillator frequency three times and the second stage multiplies the first five times, thus giving at Y a resultant frequency fifteen times that of the oscillator LO.

This resultant frequency is then of such value that when beat against the incoming signal frequency picked up upon antenna A1 the beat frequency is the same as the local oscillator LO frequency. The receiving circuit includes an electron discharge tube 3 for transferring the heterodyned energy to an intermediate frequency amplifier IFA. The intermediate frequency is greatly amplified and part of this amplified frequency from the intermediate frequency amplifier IFA is fed from the output circuit 5 into the grid circuit GC of the local oscillator as shown. As stated, the local oscillations are quite feeble so that a fairly strong output from the amplifier IFA when fed to the grid of the oscillator will, through "frequency attraction", hold the oscillator at the frequency of the amplified beat signal or if the oscillator frequency is not too greatly different, will force it into oscillation at that frequency.

Now, if the frequency of either the transmitter or the local oscillator LO should vary slightly or should drift, the intermediate frequency would change accordingly, but the oscillator frequency would be forced to follow it and would be changed as much as the original frequency change. This change would be multiplied fifteen times through the frequency multiplier and would change the local beating frequency fifteen times as much as the original frequency variation. This would produce a correction in the opposite direction of the intermediate frequency. Equilibrium would be reached with a net change in the intermediate frequency of only one-sixteenth of the actual frequency change of the transmitter or local oscillator and would, therefore, greatly diminish the effect of signal frequency variations or drift.

Another portion of the oscillator frequency energy is fed onto the cable line CL1 to the farther distant receiving station. This station has a frequency multiplier F'M' similar to that at the first receiver. The frequency from the first station is here amplified and multiplied and used as the beating frequency to produce exactly the same intermediate signal frequency as at the first station. This intermediate is then returned via the

cable line CL2 to the first station where it is combined in combining tube CT with the same signal frequency produced there by receiver R1. The combined signal is then amplified by line amplifier LA and beat by an intermediate frequency oscillator IFO, detected in detector D and fed to the central office via the cable line CL3 as audio frequency.

The combining unit may be simple as it need 10 provide only for the adjustment of amplitude and phase of the two signals, the frequencies of necessity being identical.

It is to be clearly understood that my present 15 invention is not to be limited to the frequency values indicated on the drawing nor to the ratios stated in the specification for these are given only by way of example.

Among the advantages which the foregoing set-up has are: (A) The arrangement decreases frequency variations or drift in the resultant audio signal to a small fraction, here one-sixteenth, of the actual signal changes; (B) The arrangement provides a combining method which is stable in adjustment; (C) The system provides exactly the 25 same frequency for combination from several receivers; and (D) The arrangement gives control of the entire receiving system to one station once the desired transmitter has been tuned in. This eliminates the necessity of continually matching 30 or adjusting the signal at both receivers and makes for stability.

Moreover, my invention has other uses than the one described hereinabove. For example, under 35 certain circumstances it would be highly desirable to be able to transmit a frequency by means of wire lines from one point to another a mile or two apart, which frequency will have an absolute relationship to another higher frequency at the originating point. For instance, such an arrangement could be used for checking at the distant point of the actual frequency of a radio transmitter, and for the comparison of this frequency against a frequency standard located at the distant point. If the frequency of the transmitter is used directly there is apt to be serious 45 difficulty involved in transmitting this frequency such a distance due to the high attenuation of radio frequency when transmitted over wire transmission lines. If a lower frequency could 50 be used the difficulties involved in transmitting that frequency would be diminished in proportion to the lowering of the frequency. However, this is subject to the drawback that normally it is not possible to ascertain 55 absolute relationship between the high frequency and the lower frequency to be transmitted to the distant point. The method outlined hereinabove could be directly applied to this case. Instead of a pick-up coil connected to an antenna system as 60 shown, a pick-up coil should be provided which would be in inductive relation to one of the radio frequency power circuits of the transmitter to be measured.

The voltage induced by this pick-up coil would 65 operate through the frequency stabilization system as previously outlined and the operator would merely have to tune the local oscillator and frequency multiplication stages until the oscillator is pulled into positive control of the frequency 70 picked up from the transmitter. If a portion of this frequency is picked off by transmission line CL1 and this frequency instead again heterodyned to produce an audible note which could 75 be observed by the operator when tuning the

oscillator and frequency multiplication stages it would give a positive and rapid indication as to when the control of the oscillator had been locked into step with the frequency picked up from the transmitter. It would be observed 5 whether the audible frequency shifted sharply when this pick-up coil circuit was opened or closed.

The pick-up coil does not necessarily have to be applied to the final stages of the transmitter, 10 but could be applied to the crystal output amplifier, the relation of whose frequency to that of the output frequency of the transmitter is definitely known. The relation of this crystal frequency to the heterodyned frequency produced 15 by the frequency stabilization circuit also being known, when this frequency is transmitted to the distant point and precisely measured the actual frequency of the transmitter could be readily determined. 20

Having thus described my invention, what I claim is:

1. The method of radio reception which includes picking up radio frequency energy, locally generating energy, frequency multiplying the 25 locally generated energy to a value in frequency such that the multiplied frequency energy when heterodyned with the picked up energy produces a beat equal in frequency to the frequency of the locally generated energy, heterodyning the 30 picked up energy with the frequency multiplied energy, and controlling the frequency of the locally generated energy in accordance with the beat produced by the heterodyning process.

2. The method of radio reception which includes picking up radio frequency energy at a plurality of separated points, locally generating energy, frequency multiplying the locally generated energy so that when the frequency multiplied energy is heterodyned with the picked up 40 energy the resultant beat equals in value the frequency of the locally generated energy, heterodyning the frequency multiplied energy with the picked up energy and utilizing the beat produced by the heterodyning process to control the frequency of the energy locally generated. 45

3. A radio receiving system comprising an antenna, a local oscillation generator, a frequency multiplier for frequency multiplying the energy generated by said generator to a suitable value 50 such that when the frequency multiplied energy is heterodyned with the energy picked up by the antenna the resultant beat is of a value equal in frequency to the frequency of the local generator, and means for applying the beat energy derived 55 from the heterodyning process to the local oscillator in such a way as to lock the local oscillator into step with the beat frequency energy.

4. In a receiving system, a plurality of separated antennae, a single local oscillation generator means for frequency multiplying oscillations generated by said generator to a value in frequency such that when the multiplied frequency is heterodyned with the energy picked up upon the antenna the resultant beat frequency energy 65 equals in frequency value the frequency of the local oscillation generator, means for locking the local oscillator in step with the beat frequency energy so produced, and means for combining beat frequency energies derived from energies 70 picked up upon each of said antennae.

5. In a receiving system, an intermediate frequency amplifier, a heterodyne detector adapted 75 to receive modulated carrier frequency energy

and to impress upon said amplifier waves of a beat frequency, an oscillator operable under control of energy from said amplifier to generate waves of said beat frequency, and means including a frequency multiplier network connecting said oscillator on the output side thereof with said heterodyne detector, thereby to provide a wave the frequency of which is maintained suitably different from the frequency of said carrier energy so that, when heterodyned therewith, the

resultant waves of beat frequency are held substantially constant.

6. A system in accordance with claim 5 and having a plurality of independent energy collectors in combination with a separate heterodyne detector and intermediate frequency amplifier for each collector, and a utilization circuit including a second detector having a plurality of control electrodes each adapted to be fed with energy from a respective one of said amplifiers. 5
